United States Patent Office.

PETER BURNS, OF SYRACUSE, NEW YORK.

Letters Patent No. 103,004, dated May 10, 1870.

IMPROVEMENT IN SEATS FOR HARNESS-SADDLES.

The Schedule referred to in these Letters Patent and making part of the same.

To all whom it may concern:

Be it known that I, PETER BURNS, of Syracuse, in the county of Onondaga and State of New York, have invented new and useful Improvements in Gig-Trees; and I do hereby declare the following to be a full, clear, and exact description thereof, sufficient to enable others skilled in the art to which my invention appertains to make and use the same, reference being had to the accompanying drawings making part of this specification, in which—

Figure 1 is a top view of my invention;
Figure 2 is a front view of the same;
Figure 3 is a bottom view;
Figure 4 is a back view; and
Figure 5 is a side elevation, partly in section.

Similar letters of reference indicate like parts in the several figures.

My invention relates to an improvement in gig-trees or harness-saddles, and consists in a novel mode of constructing the seat of the tree, as will be herein-after more fully specified.

The seats of gig-trees or harness-saddles are either made of solid metal, or wood, and secured to the crotch by bolts and screws, or are made with a metallic shell with the inside of wood, in order that the leather may be more easily tacked thereto. Both of these forms are, in many respects, objectionable, and the object of my invention is to overcome these objections.

Referring to the drawings—

A may represent a crotch of ordinary construction and form, the crupper B cast in one piece therewith.

C is the seat, secured to the crotch by means of a screw, *a*, fig. 3, and a bolt and nut, *b*, the head of the bolt extending through both tree or crotch and seat.

The seat C is cast hollow, in order to lessen the weight thereof, and is of the usual curved form.

A bridge, *p*, is cast over this cavity or hollow, and is provided with a female thread, into which the screw *a* fits, and, with the bolt, holds the seat to the crotch.

By casting the seat hollow it will be readily seen

that there is less weight in the saddle, and also that there is a great saving in material.

The back or highest part of the seat *c* is provided with any number of suitable holes *d d d*, which are made, preferably, flaring each way, and are intended to receive blocks of wood or other suitable substance *e*, which are driven therein, and thus form beds for the tacks or screws which are used to secure the leather covering to the seat in the usual manner.

The blocks or plugs of wood are, of course, cut down even with the surface of the seat, so that it will present a level surface, and, as the plugs extend through the seat, they thus afford a double tacking-surface, whereas only one tacking-surface was before presented, in those in which wood and metal were combined.

The plugs are driven in the holes, and become compressed in the middle, but bulge out at both ends, entirely filling the flaring ends of the holes, and thus preventing them from working or falling out.

It will be seen that, by this construction, not only a strong and durable seat is produced, but at the same time one to which leather or other material is readily and easily attached.

Having thus described my invention

What I claim as new, and desire to secure by Letters Patent, is—

1. The seat C of a gig-tree or harness-saddle, provided with the holes *d d*, filled with wood or other equivalent substance, substantially as set forth.

2. The seat C of a gig-tree or harness-saddle, formed with a cavity, *h*, bridge *p*, and holes *d d*, all cast in one piece, substantially as herein shown and described.

To the above specification of my invention I have signed my name this 16th day of April, 1870.

PETER BURNS.
